Primary Examiner — Sharon S Oum(74) *Attorney, Agent, or Firm* — McGarry Bair PC(57) **CLAIM**

The ornamental design for a ceiling fan motor housing, as shown and described.

DESCRIPTION

FIG. 1 is top perspective view of a motor housing in the environment of a ceiling fan;

FIG. 2 is a bottom perspective view of the motor housing of FIG. 1;

FIG. 3 is a top view of the motor housing of FIG. 1;

FIG. 4 is a bottom view of the motor housing of FIG. 1; and, FIG. 5 is a side view of the motor housing of FIG.

Portions of the ceiling fan motor housing and ceiling fan environment shown in broken line form no part of the claimed design.

1 Claim, 5 Drawing Sheets(56)
